ATTORNEY

UNITED STATES PATENT OFFICE.

CARL V. HELMSCHMIED, OF MERIDEN, CONNECTICUT, ASSIGNOR TO THE
C. F. MONROE COMPANY, OF SAME PLACE.

DESIGN FOR A TABLE-VESSEL.

SPECIFICATION forming part of Design No. 21,878, dated October 4, 1892.

Application filed August 18, 1892. Serial No. 443,447. Term of patent 3½ years.

To all whom it may concern:

Be it known that I, CARL V. HELMSCHMIED, a citizen of the United States, residing at Meriden, in the county of New Haven and State of Connecticut, have invented and produced a new and original Design for Vessels for Table Use; and I do hereby declare the following to be a full, clear, and exact description of the invention, such as will enable others skilled in the art to which it appertains to make and use the same.

Referring to the accompanying drawings, Figure 1 is an elevation of a table-salt, showing my design; Fig. 2, a cross-section of the same.

Similar numbers of reference denote like parts in both figures of the drawings.

The leading feature of my design consists in an alternating series of concave and convex surfaces spirally disposed in the direction of the height of the vessel, and a spiral rib between such surfaces.

1 denotes the concave, and 2 the convex surfaces.

3 denotes the ribs.

I claim—

The design for vessels for table use, substantially as herein shown and described.

In testimony whereof I affix my signature in presence of two witnesses.

CARL V. HELMSCHMIED.

Witnesses:

WILLIS I. FENN,
C. F. MONROE.
